UNITED STATES PATENT OFFICE.

OSCAR H. PIEPER AND ALPHONSE F. PIEPER, OF SAN JOSÉ, CALIFORNIA.

DENTAL ENGINE.

SPECIFICATION forming part of Letters Patent No. 562,742, dated June 23, 1896.

Application filed January 29, 1895. Serial No. 536,565. (No model.)

To all whom it may concern:

Be it known that we, OSCAR H. PIEPER and ALPHONSE F. PIEPER, citizens of the United States, and residents of San José, in the county of Santa Clara and State of California, have invented certain new and useful Improvements in Dental Apparatus, as herein-after described; and we hereby declare that the specification and drawings hereto attached constitute a complete description of our improvements and of the manner of constructing and applying the same.

Our invention relates to dental apparatus employing motive power to operate various implements, and to the method of arranging such motive power and the elements of transmission, to secure convenience and celerity in the various operations to be performed.

Our improvements consist in the construction, arrangement, and combination of parts, substantially as will be hereinafter described and claimed.

Referring to the drawings herewith, illustrating the manner of applying our invention, Figure 1 shows a motive apparatus mounted according to our invention. Fig. 2 is an enlarged partial side view of the motor in a plane opposite to Fig. 1.

Similar letters of reference are employed to designate like parts in the two figures of the drawings.

Referring to the drawings, A is a wall, to which the swinging bracket B is attached by the pivotal bearings C C.

D is an electric motor inclosed in a spherical case, and made in accordance with our application for Letters Patent, Serial No. 509,585, filed April 30, 1894, for improvements in electrical apparatus for operating dental implements, but such a motor can be of any form or nature that admits of suspension in a similar manner. This motor D we support in a gimbal-frame E, which is suspended by a cord or cable F, which contains the conducting-wires, passing over the pulleys G' G², down along the wall A, and to a rheostat H, the latter so arranged as to be controlled by the foot of an operator.

Through the cable or cord F and the gimbal-frame E passes the required wires for con-

ducting electrical current and controlling the movements of the motor D, entering through the axes Q or R, or both, in the usual manner.

The bracket B is made in two parts, having a telescopic section I, that can be moved out or in, and fastened in any required position by means of a screw J, so the flexible driving-shaft K and the implements L can be brought over or to either side of a dental chair M, as seen in Fig. 1.

On the cable or cord F we place a counter-weight N, that balances or partially balances the motor D, so the latter will remain after adjustment at various heights from the chair M.

When the flexible shaft or transmission-tube K is to be led off at an angle, or horizontally in respect to the motor D, we provide a latch or detent O, that slides on the gimbal-frame E and engages a notched sector P, attached to the motor D, so the latter can be fixed in various positions, or at different angles, as seen in Fig. 2.

The constructive details of the motor D, the flexible shaft K, dental implements L, and the rheostat H being set forth in our application for Letters Patent hereinbefore cited, and in our application for Letters Patent, Serial No. 509,584, filed April 30, 1894, in electrical controlling apparatus for motors, no further description of these elements is required here.

Having thus explained the nature and objects of our invention and the method of constructing the same, what we claim as new, and desire to secure by Letters Patent, is—

1. In a dental apparatus, the combination of an implement-operating motor having an axis, a frame in which the axis is adjustably supported, a counterweighted cable on which the frame is suspended so as to be vertically adjustable, and means for holding the motor in any position to which it may be adjusted about its axis, substantially as described.

2. In a dental apparatus, the combination of the motor, the gimbal-frame in which it is supported, the suspending rope or cable attached to the gimbal-frame, the movable bracket having pulleys for the said rope or cable, a counterweight on the rope, substantially as described.

3. In a dental apparatus, a suspended mo-

motor, a gimbal-frame holding the same, to permit it to be adjustable about its own axis, and a latch or detent to hold the motor in the various positions to which it may be adjusted together with means for engaging the latch or detent, substantially as described.

4. In a dental apparatus, the combination of an implement-operating motor having a horizontal axis, a gimbal-frame supporting it, a pulley attached to the said axis, a rope or cable attached to the said frame, a notched sector on the motor, and a sliding de-

tent on the frame that engages the sector, substantially as described.

In testimony whereof we have hereunto affixed our signatures in the presence of two witnesses.
